ABSTRACT OF THE DISCLOSURE

A buoyant plastic body has a tubular element extending through said buoyant body forming a diametrical tubular passage therethrough. The tubular element has an extension protruding exteriorly from the body as a tubular stub. A plurality of substantially radially extending circumferentially spaced rib elements are secured to the exterior surface of the stub and to the adjacent outside wall of the tubular body. These rib elements are molded to the stub and also to the buoyant body exterior wall. A clamp device may be provided upon the stub and the buoyant body, tubular element and ribs may be molded from the same plastic material and are of the same thickness as the walls of the body and the tubular element.

The present invention relates to a buoyant body of plastic furnished with a tubular passage therethrough particularly, but not restrictively, a hollow buoyant body referred to as a rod buoy, because a mooring or marking rod is threaded through and positioned in the tubular passage.

In the following the invention shall be described in connection with rod buoys, but it shall be understood that the invention can be practised with all kind of buoyant bodies having through-going openings, such as fishing gear, floats, fenders, etc.

Rod buoys made from a plastic material have in recent years come into extensive use, in particular for fishing gear and for mooring purposes. Such buoys are provided with a through-going passage by means of a tubular element which is sealingly molded to the body wall. The rod positioned through the passage may have an upper free standing portion which is provided with a fastening eye for a rope or the like or provided with a marking device, for instance a flag, making the buoy more easily to spot when floating in the sea, the lower portion of the rod being positioned below the sea surface being provided with a weight in order to keep the rod and the buoy in upright position when floating in the sea. In order to fasten the rod to an inflateable hollow body, i.e. to prevent that the rod is sliding in the passage, the tubular element can be made from a flexible material having in result that the tubular element, when the buoyant body is inflated, due to the air pressure will be pressed firmly against the rod and thereby lock same to the hollow body. Such a rod buoy is described in Norwegian Patent No. 90,515. The rod can, however, be fastened to the buoy otherwise, most simply by positioning a thickening on the rod adjacent each mouth opening, thus preventing the rod from sliding in the passage.

Rod buoys which shall be used as mooring buoys,

2

fenders and the like, are frequently provided with a throughgoing steel rod which at the passage mouths on each side of the buoy is furnished with disc-like stoppers resting firmly against the outside of the float proper. See for instance U.S. Patent No. 2,381,394.

Regardless of which purpose the buoy shall serve or how the rod is being fastened to the buoy, there will between the rod and the float proper be prevalent various kinds of stresses in the form of tensions, bending- and torsional stresses because the rod will be anchored to some object or other, while the floating buoyant body constantly is subjected to forces from the sea in the shape of waves, streams and the like.

These stresses will concentrate themselves in the region between the joint between the tubular element and the buoy wall, and sooner or later a fatigue failure may occur in the plastic material in the said region. In order to avoid this it therefore has been customary to provide the tubular element and/or the body with reinforcements by means of increasing the thickness of the material, but this means has not proved to be a satisfactory solution, among other reasons because during the molding operation of the buoyant body it is a difficult task to achieve the proper throughgoing curing of the material, particularly when the body is provided with local thickenings. A special curing step of these parts, for instance by applying more heat to same, very easily will lead to an over-curing of the adjacent thinner parts of the body having as a result that these will be weakened, a fact which makes it more feasible to cure such thicker parts somewhat less than ideal, but thereby these thicker parts will of course not be as strong as intended. Furthermore such thicker material parts of the float will demand longer production time, lessen the reproducability and also result in a heavier and more expensive product. Applicant's U.S. Patent No. 3,081,493 illustrates examples of such reinforcements.

The chief object of the invention is to overcome the above described difficulties and the draw-backs in connection with known buoyant bodies of this type and this is in accordance with the invention accomplished in that said tubular element has an extension in the shape of a free standing tubular stub protruding out from the wall of the buoyant body, a plurality of substantially radially extending circumferentially spaced rib elements being molded to the cylindrical outside surface of the stub and to the bordering outside wall of the buoyant body.

The rib elements on the buoyant body in accordance with the invention act as a combination of reinforcing ribs and a spring means, since the ribs will flexibly resist relative movements between the rod and the buoy, when tension, bending or torsional stresses or a combination of such are acting between the rod and the buoyant body so that neither wear nor fatigue failures will occur in the plastic material in the buoy.

Furthermore a hollow body or float in accordance with the invention can be made having substantially uniform goods thicknesses, a fact which to a large degree facilitates the molding and the correct curing of the plastic material, a reproducible production and also result in a product relatively lightweighted.

For a complete understanding of the invention, refer-

ence shall be made to the detailed description which follows and to the accompanying drawings, in which:

FIGURE 1 is a side view of a rod buoy in accordance with the invention;

FIGURE 2 is on a larger scale a fragmentary sectional view of the lower mouth section of the buoy shown in FIGURE 1;

FIGURE 3 is aside view on a larger scale of the upper part of the buoy shown in FIGURE 1;

FIGURE 4 is a sectional view through the mouth portion of a modified embodiment of a buoy in accordance with the invention, said section taken along the plane IV—IV shown in FIGURE 5, and

FIGURE 5 is a plan view of half of the object shown in FIGURE 4.

FIGURE 1 shows a side view of a buoy 2 in accordance with the invention. The buoy is of ovoid shape provided with a throughgoing passage by means of a tubular element 4 molded integral with the body proper in a per se known fashion. As appearing best from the fragmentary view shown in FIGURE 2, the tubular element 4 is molded to the buoy wall 6 at the junction 8. The tubular element has an extension protruding out from the outside surface of the body wall in the shape of a stub 10, and in the transition zone between the buoy wall and the tubular element are provided a number of circumferentially spaced rib-like elements 12—12, each of which is molded to the buoy wall as well as to the tubular element, along edges 14 and 16 respectively, so that each rib 12 has an outwardly pointing free edge 18. In the shown embodiment of the invention each rib ends a small distance short of the extremity of the pipe stub there is provided a round cylindrical stub 20 for the support of a clamp 22 which by means of a screw 24 can be clamped onto a rod or the like 26 which beforehand is threaded through the passage. As previously mentioned the rod can be attached to the buoy also by making the tubular element 4 from a relatively soft or flexible material which by inflating the buoy will be pressed against the rod.

The number of the ribs and their configuration is not particularly critical, but it constitutes a feature of the invention that the rib thickness shall not deviate substantially from the thickness of the wall in the buoy and the tubular element.

The ribs at the other mouth opening 30 of the buoy are, as is best shown in FIGURE 3, somewhat differently shaped since the buoy here ends with a substantially plane end surface 32, so that the ribs 34 have a likewise substantially straight joint to the buoy as well as to the tubular element.

FIGURES 4 and 5 show a different embodiment of the invention, wherein the buoy wall 40 in the region 44 about the mouth opening 42 is curved inwardly towards the center of the buoy, the free standing edge 52 of each rib 56 joining the body wall in a tangential relationship at 54.

The ribs 56 are here shown as extending in a straight radial plane, but it shall be understood that it is within the scope of the invention to design the ribs so that they curve radially outwards such as indicated with dotted lines 57 in FIGURE 5. The embodiment of the invention as shown in FIGURES 4 and 5 is primarily designed to be used for mooring buoys and the like, the free edges 52 of the ribs 56, and the angular mouth edge of the tubular element 50 is positioned in a common plane standing perpendicular to the axis of the tubular passage.

It will be understood that there is no hindrance to giving the mouth region on a buoy in accordance with the invention a shape different from the embodiment shown in FIGURES 2, 3 or 4, for instance in the shape of a combination of features from the embodiment shown in FIGURES 3 and 4 respectively, so that the ribs extend outwardly as well as inwardly relative to the outside surface of the buoy.

A buoy devised in accordance with the invention will be strengthened in aspect of various forms of stresses or combinations thereof.

Usually the rod will be fixed to the buoyant body so that it cannot turn relative to same, for instance by means of a clamp device as shown. Between the rod and body there will be present more or less continuous torsional and axial stresses, which, however, are initially received by the rib elements, and thereafter transferred and distributed across a relatively large surface area of the buoy. In the embodiment shown in FIGURE 1 most of the forces between the buoy and the rod will naturally be transferred via the clamp device 22, although practice has shown that after a short period of use in the open sea, the rod will adhere to the tubular passage wall all along the passage due to accumulation of salt, dirt, etc.

As will be understood axial forces acting between the buoyant body and the rod likewise will be received by the rib elements and effectively transferred and distributed across the buoy wall.

A correct transfer and distribution of forces and stresses between the rod and buoy are enhanced when the goods thicknesses of the buoy wall, the tubular element and the ribs are made about the same. This means that all goods subject to stresses are stressed or able to undergo elastical deformation of the same order, i.e. stress concentrations are avoided.

The fact that all parts in a buoyant body in accordance with the invention have about the same goods thicknesses means furthermore that the entire buoyant body shall be subjected to the same curing treatment. This circumstance to a large degree facilitates a reproducible and faultless production.

We claim:

1. An ovoid plastic buoy having walls comprising a buoyant body of flexible plastic material, a tubular element formed integral with the body walls of said buoyant body forming a tubular passage through said body from one point on the outside surface to a diametrically opposed second point on the outside surface, said element having an extension protruding out from the wall of said buoyant body in the shape of a free standing tubular stub and a plurality of substantially radially extending circumferentially spaced elongated rib elements molded to the outside surface of said stub and to the adjacent outside wall of said buoyant body, said rib elements, tubular element and body walls being of the same material and thickness throughout to promote uniform curing and strength thereto; and an integrally molded unobstructed hub portion on said stub adjacent the rib elements, and clamp means thereon for deformably initially clamping the tubular element to a rod element inserted therein for association with said buoyant body such as the staff of a marker flag.

2. An ovoid plastic buoy having an upper pole of major amplitude surmounting a lower pole of minor amplitude when in the normal operating use, comprising in combination:

- (a) an airtight inflatable hollow body including walls of non-rigid, plastic material and being symmetrical about a vertical central axis;
- (b) a tubular sleeve element formed of relatively flexible plastic integral with said walls and body and disposed on the vertical axis to form an open tubular passage completely through said body from pole to pole;
- (c) said tubular element having at least one end projecting from an end in the form of a free standing tubular stub;
- (d) a plurality of elongated, substantially radially extending circumferentially spaced exterior rib elements integrally molded to the surface of said stub and to the adjacent outside wall of said body; said ribs, tubular element and body being substantially of the same

material and thickness throughout to promote uniform curing and added strength thereto of said plastic buoy; and

(e) an integrally molded hub portion on said tubular stub adjacent said ribs and clamp means thereon for deforming the tubular element and clamping a rod element as of a marker flag insertable through said tubular element for association with said buoy.

3. A buoy as defined in claim 2 wherein said tubular element projects beyond the body at both poles to form two stubs, and said rib elements are integrally molded to and interconnecting the outer surface of each stub and said body adjacent each pole; and the rib elements formed at the lower pole having the said hub portion molded adjacent thereto.

4. A buoy as defined in claim 3 wherein the lower pole rib elements are substantially longer than those at the upper pole.
